CHARLES H. SMOOT, OF MAPLEWOOD, NEW JERSEY.

STEAM-ACCUMULATOR CONTROL.

Application filed August 15, 1925. Serial No. 50,519.

The present application is a continuation in part of my prior application filed June 9, 1925, Serial No. 35,952.

This invention relates to steam accumulators used for storing the heat of waste steam such as the exhaust of high pressure engines, in a tank of hot water, to the end that the energy so stored may be drawn off at some lower pressure for other uses, as for example supplying steam to water gas generators. A pressure regulator responsive to the delivery pressure governs the amount of steam flowing from the accumulator so that the delivery pressure will be held approximately constant. When the supply of steam from the accumulator falls short of the demand, it is desirable to supplement it with steam from high pressure source until the accumulator is again able to meet the demand. It is further desirable that the controlling means for regulating the draft of steam from the accumulator be connected with the controlling means for admitting high pressure steam, to the end that high pressure steam will not be drawn upon until the accumulator supply has reached a predetermined minimum and then only in sufficient amount to make up the deficiency of the accumulator, and further that upon the accumulator regaining its power to supply the demand the high pressure supply will be proportionately discontinued and shut off altogether when the accumulator supply rises above the said predetermined minimum.

35 The object is to insure that no waste of high pressure steam will occur when the accumulator is able of itself to supply the demand. It is further desirable in case the supply to the accumulator exceeds the demand to such an amount that the pressure in the accumulator rises to a predetermined maximum, that a relief valve shall be opened to the atmosphere to prevent any further increase in the delivery pressure.

45 My invention comprises a combination of linkages that will, upon a rise in pressure in the delivery pipe, automatically close in succession the high pressure valve, the low pressure valve and finally on a continuation of pressure rise open a relief valve in the delivery pipe.

The accompanying drawing shows a sectional view of apparatus designed to carry out the invention.

55 In the drawing, 1 represents the tank of an accumulator, in the delivery pipe 2 of

which is a stop valve 3. 4 is a relief valve which may be an ordinary safety valve held closed by a weight or a spring against the steam pressure. 6 is a low pressure regulating valve controlling the flow of steam from the accumulator delivery pipe 2 to the pipe 7 which serves to conduct the steam to any suitable means of consumption. From the pipe 7 a pipe 8 leads to a chamber 9 having a diaphragm 10. A rod 11 connected to the diaphragm is articulated to the end of a lever 12 pivoted at 13. A spring 36, the tension of which is adjustable by nut 37 on screw 38, gives a means of adjustment to regulate the loading for the low pressure. The other end of this lever is articulated at 14 to a rod 15 that is clamped to a transverse member 16. The member 16 has a rod 17 passing freely through it and articulated at 18 to an intermediate point on the lever 19, one end of which at 20 is pivoted to a rod 21 for operating a lever 22 controlling the low pressure valve 6. The other end of the lever 19 is pivoted at 23 to a rod 24 articulated at its other end to a lever 25 that operates a high pressure valve 26. A weight or other suitable means 27 is so connected with the low pressure valve 6 as to tend to close the same. A fixed stop 28 is provided to arrest the motion of the valve when it is fully open. A still larger weight or equivalent means 29 is carried by the high pressure valve 26 in such a way as to tend to close the same. The weight 29 by its excess over the weight 27 or by being connected to a longer arm of the lever 19 than the valve 6, insures that when the rod 17 pulls on the lever 19, it will first operate the low pressure valve 6 until the same is fully open and will then if still further motion takes place commence to open the high pressure valve 26. The rod 17 is guided in a fixed guide at 30 and has an abutment at 31 secured to it, which abutment provides a means whereby the member 16 may move the rod 17 within certain limits. The relief valve 4 is shown with a lever 32 operating a connecting rod 33 guided at 34 and having a stop secured to it at 35 whereby it also may be moved by the reciprocating member 16 within certain limits. A check valve 5 may be used to prevent the high pressure steam passing into the accumulator.

The operation of the apparatus is as follows:—Upon the demand for steam in the pipe 7 being increased, a diminution in pres-

sure in chamber 9 will ensue, which will cause the lever 12 to move in such a way as to shift the member 16 until it comes in engagement without abutment 31 on rod 17. 5 The motion of rod 17 by moving lever 19 using the mechanism with weight 29 as a fulcrum, will pull on rod 21 and open the low pressure valve 6. As the demand increases the valve 6 will continue to open, 10 keeping the pressure in pipe 7 substantially constant until the said valve is fully open and rests against the stop 28. As the rod 21 can then move no further, it in turn becomes the fulcrum for the lever 19 and 15 further movement of the member 16 will result in a pull on the rod 24 and an opening of the high pressure valve 26. At this point, steam which thus far has been drawn only from the accumulator, will be supplemented by steam drawn from the high pressure pipe and the amount of this supplemental draft will be in exact proportion to the inability of the accumulator to supply the demand. When the accumulator again 20 is equal to supplying the demand reverse operations will take place, the high pressure valve closing first entirely before the low pressure valve commences to close. Should the pressure in the delivery pipe 7 25 continue to increase above a predetermined maximum the further movement of the diaphragm 10 will, by causing the member 16 to impinge on abutment 35, move rod 33 and open the relief valve 4 to the atmosphere 30 against the force of a weight 36' which tends to hold said valve closed. 35

It will thus be seen that the high pressure valve and the low pressure valve are so connected by linkages as to open and close in sequence in accordance with means responsive to the pressure in the delivery pipe and that there is a limited amount of lost motion between the sequential events and that the sequence may be further extended to the operation of the relief valve. 40 45

I claim:—

In combination with a steam accumulator, a delivery pipe leading therefrom, a control mechanism for regulating the pressure of steam in the delivery pipe comprising a low pressure valve regulating the supply to said pipe from the accumulator, a high pressure valve regulating the supply of high pressure steam to said pipe, a relief valve for opening a connection from said delivery pipe to a lower pressure, means responsive to the pressure in the delivery pipe, a loading means therefor and linkages connecting the three valves and the pressure responsive means comprising an intermediate member 50 engaging in sequence the high pressure valve, the low pressure valve and the relief valve when moving in response to increasing pressure and in opposite sequence when the pressure falls with a limited movement between the said engagements, whereby as the pressure increases in the delivery pipe the high pressure valve will first be closed, then the low pressure valve and finally the relief valve opened. 55 60 65
